DESIGN FOR A SKILL TESTING GAME DEVICE

Melvin J. Binks, River Forest, Ill., assignor to J. H. Keeney & Co., Inc., Chicago, Ill., a corporation of Illinois

Application February 14, 1940, Serial No. 90,255

Term of patent 7 years

To all whom it may concern:

Be it known that I, Melvin J. Binks, a citizen of the United States, residing at River Forest, in the county of Cook and State of Illinois, have invented a new, original, and ornamental Design for a Skill Testing Game Device, of which the following is a specification, reference being had to the accompanying drawing, forming part thereof.

In the drawing:

Fig. 1 is a perspective view of a skill testing
game device showing my new design.

Fig. 2 is an elevational view taken from the rear of the game device.

Fig. 3 is a plan view of the top portion only.

I claim:

The ornamental design for a skill testing game
device, substantially as shown.

MELVIN J. BINKS.
